UNITED STATES PATENT OFFICE.

FRANCIS S. DUNHAM, OF CHICAGO, ILLINOIS, ASSIGNOR TO KENNICOTT WATER-SOFTENER COMPANY, A CORPORATION OF ILLINOIS.

WATER-SOFTENING APPARATUS.

993,663.

Specification of Letters Patent.

Patented May 30, 1911.

Application filed March 2, 1910. Serial No. 546,819.

To all whom it may concern:

Be it known that I, FRANCIS S. DUNHAM, a citizen of the United States, residing at Chicago, in the county of Cook and State of Illinois, have invented a new and useful Improvement in Water-Softening Apparatus, of which the following is a specification.

My invention relates to an improvement in the class of water-softening apparatus in which the water to be purified is subjected, in its course to the settling-tank of the apparatus, to the precipitating action on matter in the water which renders it hard, of suitable chemical substances supplied to the water, for mixing with it, in proper proportion; and it relates, more particularly, to an improvement in the manner of automatically supplying the chemical in the required proportion to the water to be softened.

In the accompanying drawings—Figure 1 is a broken view in sectional elevation of a known type of water-softening apparatus containing my improvement, the view presenting only so much of the apparatus as is required to enable the improvement to be readily understood, and Fig. 2 is a similar view of the apparatus showing my improvement in one of various modified forms in which it may be provided.

The settling-tank 3, having a discharge-spout 4 leading from it near its upper end, at the water-level therein indicated at 5, contains a downtake-conduit 6, shown to be 35 downwardly flaring and surrounded, below the water-level, by a screen 7. Upon rails 8 on the upper end of the tank is supported a tank 9 provided with a draw-off spout 9¹ for emptying it. Above the tank 9 is the 40 water-box 10 containing a vertical perforate partition 11 which divides it into the relatively smaller and larger compartments 12 and 13, this box receiving from a spout 14 the raw water to be treated. A valved 45 spout 15¹ discharges the water from the compartment 12, through a relatively small opening 15 in its bottom, into the tank 9, and from a relatively large opening 16 in the bottom of the compartment 10 depends a 50 pipe 17 into a mixing-tank 18 in the upper-end portion of the conduit and which overflows into the latter. The pipe 17 extends nearly to the bottom of the mixing-tank, shown to be of hopper-form, and a valved 55 spout 19, for emptying the tank, when de-

sired, depends from a discharge-opening in the apex of the bottom. In the tank 9 is a float 20.

The parts thus described present no features of novelty, being those employed in the aforesaid known type of apparatus selected for illustrating my improvement, which, however, is applicable to any construction of water-softening apparatus in the class referred to; and those parts are the same in Fig. 1 as in Fig. 2, except that in the latter, instead of a pipe 17 and mixing-tank 18, a spout 16¹ is provided to discharge into a funnel-like mixing chamber 18¹ dipping into the tank 3 through the upper end of the conduit 6.

In the arrangement shown in Fig. 1 for applying my improvement, a chain 21, on one end of which the float 20 is suspended, passes over guide-pulleys 22 and 23 on the water-box and carries on its opposite end the chemical to be used, provided in solid condition in the form of a stick 24, with an eye 25 projecting from its upper end at which to attach the chain. The chemicals of which the stick 24 is composed are those required, mixed in the proper proportions, for the particular water to be treated. For the purposes of the present case the composition of the stick may be that suitable for the treatment of the more ordinary waters requiring purification, namely lime and soda ash in the proportion of three parts of the former to one part of the latter, mixed together and molded into or otherwise provided in stick-form of suitable dimensions. The substance of the chemical stick dissolves very readily in water.

The purpose is to proportion automatically, with desirable accuracy, the supply of the chemical to the quantity of water flowing into the apparatus, the flow of which is subject to variation, however, necessitating corresponding variation in the supply of the chemical, because of the change of head in the water-box. This is automatically taken care of by the float 20. The size of the opening 15 relative to that of the opening 16 is such as to feed that proportion of the water entering the box 10 to the tank 9 which is required for making the strength of chemical solution for treating the proportion of the water which enters, at the same time, into the tank 18. As the float 20, therefore, rises in the tank 9 under the accumulation

of water in it, the stick 24 lowers into the mixing chamber 18, to a greater or lesser extent of its length, in correspondence with any change of head of the water in the box 10, and that part of the stick which dips into the water in the mixing-tank is readily dissolved thereby and mixes with it, the mixture overflowing from the tank 18 and entering the precipitating tank to act upon the water therein.

In Fig. 2 the means shown to be provided for automatically feeding the chemical are adapted for the purpose with the latter in dry and loose or pulverized form requiring it to be used in a suitable tubular holder 26 which will readily disintegrate or dissolve in water, such as tissue-paper or gelatin. The holder 26 filled with the chemical mixture is supported in a metal or glass tube 27 extending horizontally from the upper end of the tank 9 over the funnel 18¹. The holder 26 is movable longitudinally in its support for feeding it, and so much of it as protrudes beneath the spout 16¹ is washed off into the funnel by the water flowing from the spout. For feeding the holder 26, a rack-bar 28 rises vertically from the center of the float and engages a pinion 29 to work a longitudinal rack-bar 30 which enters the rear end of the holder 27 and acts as a push-bar against the adjacent end of the chemical holder.

What I claim as new and desire to secure by Letters Patent is—

35 1. In a water-softening apparatus, means for supplying to the water to be treated therein the chemical treating-material in stick-form, comprising a tank, means for proportioning the supply to the tank of said water, a float in the tank and mechanism for engaging the stick, connected with the float to be actuated by its rise to advance said stick, for the purpose set forth.

2. In a water-softening apparatus, means

for supplying to the water to be treated 45 therein the chemical treating-material in stick-form, comprising a tank, means for proportioning the supply to the tank of said water, a float in the tank, and a pulley-supported chain having one end connected with 50 the float and adapted to carry said stick on its opposite end, for the purpose set forth.

3. In a water-softening apparatus, the combination with the settling-tank, of a water-box for receiving the supply of water 55 to be treated and having relatively larger and smaller discharge-outlets, a float-tank into which said box discharges through the smaller outlet, a mixing-chamber into which said box discharges through the larger outlet, and means for supplying to the water entering said mixing-chamber the chemical treating-material in stick-form, comprising a float in the float-tank, and mechanism for engaging the stick, connected with the float 60 to be actuated by its rise to advance the stick toward the mixing-chamber, for the purpose set forth.

4. In a water-softening apparatus, the combination with the settling-tank, of a water-box for receiving the supply of water to be treated and having relatively larger and smaller discharge-outlets, a float-tank into which said box discharges through the smaller outlet, a mixing-chamber into which 75 said box discharges through the larger outlet, and means for supplying to the water entering said mixing-chamber the chemical treating-material in stick-form, comprising a float in the float-tank, and a pulley-supported chain having one end connected with 80 the float and its other end hanging over the mixing-chamber for suspending from it said stick, for the purpose set forth.

FRANCIS S. DUNHAM.
